TOY GUN

Saul Robbins, 35 Mountain Way, West Orange, N.J., and
Isaac Heller, 2080 Arrowwood Drive, Scotch Plains,
N.J.

Filed July 26, 1962, Ser. No. 71,062

Term of patent 14 years

(Cl. D34—15)

FIGURE 1 is a side elevation of a toy gun, the other side being a mirror image thereof;

FIGURE 2 is a top plan view thereof taken from the plane of the line 2—2 of FIGURE 1;

FIGURE 3 is a bottom plan view thereof taken from the plane of the line 3—3 of FIGURE 1;

FIGURE 4 is an end elevational view thereof from the plane of the line 4—4 of FIGURE 1; and

FIGURE 5 is an end elevational view from the plane of the line 5—5 of FIGURE 1.

We claim:

The ornamental design for a toy gun, as shown and described.
